[57] CLAIM

The ornamental design for a telephone apparatus housing, as shown and described.

DESCRIPTION

FIG. 1 is a side elevational view of a telephone apparatus housing showing our new design, a view of the side opposite being a mirror image of the side shown;

FIG. 2 is a top plan view thereof;

FIGS. 3 and 4 are respectively front and rear elevational views thereof;

FIG. 5 is a bottom plan view thereof;

FIG. 6 is a side elevational view of a second embodiment thereof, a view of the side opposite being a mirror image;

FIG. 7 is a top plan view thereof;

FIGS. 8 and 9 are respectively front and rear elevational views thereof;

FIG. 10 is a bottom plan view thereof;

FIG. 11 is a side elevational view of a third embodiment thereof, a view of the side opposite being a mirror image of the side shown;

FIG. 12 is a top plan view thereof;

FIGS. 13 and 14 are respectively front and rear elevational views thereof;

FIG. 15 is a bottom plan view;

FIG. 16 is a side elevational view of a fourth embodiment thereof, a view of the side opposite being a mirror image of the side shown;

FIG. 17 is a top plan view thereof;

FIGS. 18 and 19 are respectively front and rear elevational views thereof;

FIG. 20 is a bottom plan view thereof;

FIG. 21 is a side elevational view of a fifth embodiment thereof, a view of the side opposite being a mirror image of the side shown;

FIG. 22 is a top plan view thereof;

FIGS. 23 and 24 are respectively front and rear elevational views thereof;

FIG. 25 is a bottom plan view thereof;

FIG. 26 is a perspective view that is intended to be common for the three embodiments shown in FIGS. 1-15 with the housing top surface being broken across its width to indicate that the only differences between embodiments resides in variation with respect to the width of the housing;

FIG. 27 is a perspective view of the fourth embodiment illustrated in FIGS. 16-20; and

FIG. 28 is a perspective view of the fifth embodiment illustrated in FIGS. 21-25.
